UNITED STATES PATENT OFFICE.

THOMAS PARKER, OF LONDON, ONTARIO, CANADA.

CAR-HEATING SYSTEM.

No. 923,570.

Specification of Letters Patent.

Patented June 1, 1909.

Application filed May 18, 1907. Serial No. 373,347.

To all whom it may concern:

Be it known that I, THOMAS PARKER, a subject of the King of Great Britain and Ireland, residing at London, in the Province of Ontario and Dominion of Canada, have invented certain new and useful Improvements in Car-Heating Systems, of which the following is a specification, reference being had therein to the accompanying drawings.

10 The invention relates generally to a heating system for railway cars, and particularly to a dripless heating apparatus wherein the water of condensation is retained within the radiator and heated by the steam, forming substantially a combined steam and hot water system.

15 The invention consists in the novel construction of the heating apparatus, and further in the peculiar arrangement and combination of the various parts, as will be more fully hereinafter set forth.

In the drawings, Figure 1 is a view in elevation, partly broken away, of a heating system embodying my invention; and Fig. 2 is 20 an enlarged vertical central section through the valves, showing a modified form of valve for the connecting pipe or conduit.

25 In the drawings thus briefly described, A represents the preferred form of radiator employed in a railway passenger car, the piping μ being arranged in a vertical plane and inclined downwardly to drain the condensation.

30 B represents a steam supply pipe having communication with the usual train pipe (not shown), and with the radiator near its lowest point, as plainly indicated in Fig. 1.

35 C is a valve for controlling the supply pipe, and D is a drip or discharge pipe preferably 30 communicating with the radiator at a point in proximity to the supply pipe, and controlled by a suitable valve preferably of the globe type, as E.

40 F represents a connecting pipe intermediate the supply and discharge pipes, and forming a part of the radiator circuit, the radiator in this instance being a closed loop, and G is a suitable valve,—preferably of the globe type,—for the connection F controlling the discharge therethrough.

45 Means preferably in the form of a check-valve are employed for preventing the exit of the condensation, and as a matter of convenience and to simplify the construction I 50 preferably locate the check in the valve casting of the supply pipe, as shown in Fig. 1, so

that a single device will serve as the retaining means for the entire radiator.

The valve C controlling the supply pipe has its main stem g provided with a socket d 60 which receives an auxiliary stem d' carrying the check-valve e adapted to be positively seated by the main stem g when the steam supply is to be cut off.

In practice, the air and any condensation 65 that is in the radiator is first driven out and the radiator filled with steam. This is accomplished after a steam supply is provided, by opening the valves in the supply and discharge pipes and closing the valve G in the 70 portion of the radiator circuit,—namely the pipe section F,—intermediate the supply and discharge valves. The valve in the discharge pipe is then closed, and the valve G in the pipe F opened, thus providing a closed 75 radiator circuit, the steam being adapted to pass from the supply pipe into the radiator in both directions.

The condensation is retained within the 80 radiator by the check-valve e , which remains seated until the steam pressure within the radiator is less (due to condensation) than the supply, when the check is operated and live steam injected within the water, thus 85 heating it and replacing the condensation. As soon as the steam pressure is equalized, the check-valve again seats, the valve opening and closing automatically as the pressure varies, but serving at all times to retain the 90 condensation in the radiator circuit.

95 It will be obvious from the description of the apparatus that the heating is effected through the agency of steam and hot water combined, and this continues until the radiator is entirely filled. By reason of the large 100 size of the radiator ordinarily used in cars, the complete filling of the radiator circuit seldom if ever takes place during the run, so that the apparatus is always effective. In 105 unusual cases, however, where the circuit is filled with condensation, the latter may be blown out of the radiator in the same manner as the air as previously set forth.

In Fig. 2 of the drawings I have shown a 110 modified form of valve indicated by the reference-letter G' for the connection F of the flap type, comprising a main stem h , a swinging flap member i constituting the valve proper, pivoted to the casing and carrying a laterally projecting section or finger j controlled by the stem h .

From the foregoing description of the

heating system it will be obvious that merely a single drip need be open—namely, the main train pipe drip—in place of the large number ordinarily employed, generally two 5 for each car. Thus, the condensation usually wasted is utilized, and the steam pressure ordinarily required for heating is reduced to a minimum.

What I claim as my invention is,—

- 10 1. In a heating system, the combination with a radiator, of means for retaining the condensation therein, and a steam supply pipe communicating with the radiator at substantially its lowest point whereby the incoming steam and its water of condensation will heat by convection substantially all of the accumulated water of condensation during all the time the radiator is filling with said condensation.
- 15 2. In a heating system, the combination with a radiator, of a steam supply pipe communicating with the radiator at its lowest point, means for permitting air to be exhausted from the radiator, and a check-valve associated with the supply pipe serving to prevent the escape of water of condensation and to permit free entry of the steam to replace the condensed steam.
- 20 3. In a heating system, the combination with a radiator, having a steam inlet port at substantially its lowest point and intermediate its ends, of a steam supply pipe communicating with the inlet port and adapted to discharge steam within the radiator to both sides of the inlet, and means controlling the inlet acting automatically to permit entry of the steam and to prevent the escape of accumulated water of condensation.
- 25 4. In a heating system, the combination of a radiator having pipes inclined from opposite directions to a common point, means for retaining the condensation within the radiator, and a steam supply pipe communicating with the radiator at substantially its lowest point, whereby the entering

steam or its water of condensation is free to go both ways to heat the collected condensation.

5. In a heating system for cars, the combination with a radiator, consisting of a closed loop section having a portion or portions inclined downwardly for the drainage of condensation, of a valve-controlled steam supply pipe communicating with the radiator loop at substantially its lowest point, a normally closed valve controlled discharge pipe for and communicating with the radiator in proximity to the supply pipe, and a check-valve associated with the supply pipe and acting to prevent the discharge of condensation therethrough.

6. In a heating system for cars, the combination with a closed radiator circuit, of a valve controlled steam supply pipe communicating with said circuit at substantially its lowest point, a normally closed valve controlled discharge pipe also communicating with the radiator, a valve in the circuit intermediate the supply and discharge pipes, and a check-valve in the radiator circuit acting automatically to prevent the escape of condensation.

7. In a heating system, the combination with a closed radiator circuit, of a valve-controlled steam supply pipe communicating with said circuit at substantially its lowest point, a normally-closed valve-controlled discharge pipe also communicating with said radiator, a valve in the circuit intermediate the supply and discharge pipes, and automatic means for retaining condensation within the radiator and admitting steam through the condensation.

In testimony whereof I affix my signature in presence of two witnesses.

THOMAS PARKER.
